UNITED STATES PATENT OFFICE.

OLAF H. LUND, OF KENYON, MINNESOTA.

DESIGN FOR A COAT-HOOK AND HAT-HOLDER.

SPECIFICATION forming part of Design No. 27,385, dated July 20, 1897.

Application filed June 14, 1897. Serial No. 640,778. Term of patent 3½ years.

To all whom it may concern:

Be it known that I, OLAF H. LUND, of Kenyon, Goodhue county, Minnesota, have invented and produced a new and original Design 5 for a Combined Coat-Hook and Hat-Holder, of which the following is a specification, reference being had to the accompanying drawing, forming part thereof.

The drawing is a perspective view of my 10 new design. This is constructed wholly of wire, the leading features of which are the hooks 2, formed by doubling the wire upon itself and then bending the two wires in the proper hook form, the eyes 3, by means of 15 which the article may be secured to a support with screws passed through the eyes,

the outwardly-curved standard 4, formed of the two wires twisted together, and the top 5, formed by bending the wire into circular form, the plane of the curve being substantially at right angles with the standard. 20

Having thus described my invention, what I claim as new, and desire to secure by Letters Patent, is—

The design for a combined coat-hook and 25 hat-holder, as herein shown and described.

In testimony whereof I affix my signature in presence of two witnesses.

OLAF H. LUND.

Witnesses:

L. NERTIGAARD,
A. P. ROMFOG.
